UNITED STATES PATENT OFFICE.

ORVILLE W. EWING, OF DERRY, NEW HAMPSHIRE.

FLEXIBLE ROLL FOR BOOTS AND SHOES.

1,171,935.

Specification of Letters Patent. Patented Feb. 15, 1916.

Application filed October 14, 1915. Serial No. 55,804.

To all whom it may concern:

Be it known that I, ORVILLE W. EWING, a citizen of the United States, residing at Derry, in the county of Rockingham and State of New Hampshire, have invented new and useful Improvements in Flexible Rolls for Boots and Shoes, of which the following is a specification.

In the lasting of boots, shoes and slippers, particularly where the toe end is more or less pointed, there are frequently formed wrinkles or plaits which detract from the appearance of the finished shoe, and this is more particularly true when the toe portion 15 of the upper or the toe cap is made of patent leather so-called.

The object of the present invention is to provide a tool or instrumentality by means of which the wrinkles, plaits or corrugations are removed.

On the accompanying drawing,—Figure 1 represents in end view a tool or instrumentality embodying the invention. Fig. 2 represents a plan view of the same. Fig. 25 3 represents a section on the line 3—3 of Fig. 2. Fig. 4 represents a section on the line 4—4 of Fig. 1. Fig. 5 represents an end view of the hub or central supporting member. Fig. 6 represents one of the radial 30 members and Fig. 7 illustrates the pintle on which one of the members is hung.

The tool comprises a hub or central supporting member having a plurality of radial more or less flexible members hung upon 35 pivot rods arranged equi-distant from each other and at the same time distant from the center or axis of the hub or supporting member. The radial members are hung loosely so that each is capable of swinging about 40 the axis of its supporting pintle or rod and is also capable of bodily movement relatively thereto toward and from the center or axis of the hub. Said radial members consist preferably of leather of varying grades of 45 flexibility and softness, according to the particular material upon which the instrumentality as a whole is to operate. For some kinds of uppers, such as patent leather uppers or toe caps, I employ for the radial 50 members an oil-tanned leather, whereas, for shoes or toe caps formed of heavier leather, I may employ for the radial members a heavy more or less compacted leather such as sole leather. For use in connection with 55 soft kid, the radial members may be made

of leather which is relatively soft and which has a greater cushioning effect.

In operation the radial members exert a pounding or drawing action upon the toe cap or upper and tend to pound and wipe 60 out the wrinkles, plaits or corrugations.

Proceeding to a more detailed description of the tool or instrumentality, it will be observed that it is provided with a central body or hub 10 having at its ends the circumferential flanges 11 and 12. At one end the hub has an internally threaded socket 13 by which it may be screwed upon a rotatable arbor or shaft. The flange 12 has a circular series of apertures 14, through which 70 rods 15 are passed so as to extend and be supported in sockets 16 formed in the inner face of the flange 11. These rods or pintles are all parallel with the axis of the body 10, or equi-distant from each other, 75 and are all at the same time distant from the axis of said body. To hold the pintles or rods in place, I employ a circular disk 17 which abuts against the ends of the rods, as shown in Fig. 4, and which is held in 80 place by a screw 18 having a head 19. This screw is passed into a threaded socket in the outer end of the body 10, the threads being left-hand so that the rotation of the tool does not tend to unscrew the screw 18. 85 Hung upon the rods or pintles 15 are the radial working members indicated as a whole at 20. Each member consists of a piece of leather or similar material which is doubled upon itself to provide two parallel layers 90 21, 21, connected by the doubled portion 22. Between said layers there is a filler 23 which is preferably formed of relatively stiff unyielding leather, fiber or any other suitable material. These three layers are all bound 95 and held together by a line of stitches 24. It will be noted that the inner edge of the layer 23 lies at some distance from the doubled portion 22 to afford a space through 100 which the pintle or rod 15 is passed. This space is sufficient to permit a bodily movement of the operating member toward and from the axis of the hub 10. Preferably each of the operative members is slit so that the radial projecting portions of each member are capable of lateral movement relatively to each other. For instance, every other member may be provided with two slits as indicated at 25, so as to divide it into 105 three sections, and the intervening members 110

may be each provided with one slit 26 located midway between its ends. In this way the tabs or free sections of the various members are staggered with reference to 5 each other. The inner layer or filler of each member imparts more or less stiffness or rigidity thereto, whereas the outer layers serve to cushion the blow upon the work and to provide the necessary friction in 10 order to wipe the work as the member engages therewith.

When the tool is rotated, the operative members thereof stand radially outward because of centrifugal action, but each is 15 adapted to yield about its axis of movement and also to move bodily inwardly or toward the axis of the hub.

In operation the partially completed shoe, which may have been pulled over or lasted, 20 is presented to the rapidly moving tool so as to be engaged by the members at a point relatively remote from the edge of the sole portion of the shoe, and the shoe is manipulated by the operator to draw it forwardly 25 and cause the members rapidly and successively to impart a series of pounding and wiping blows upon the upper so as to pound and draw the leather toward and over said edge. This, as stated, has the effect of uniformly wiping the upper over the last and over the edge of the innersole, and of removing corrugations, plaits or wrinkles. If desired, however, this operation may be reserved until the bottoming of the shoe is 30 completed, and employed as one of the finishing steps, in which case it is efficacious in removing the wrinkles, corrugations and plaits.

Having thus explained the nature of my 40 said invention and described a way of making and using the same, although without attempting to set forth all of the forms in which it may be made or all of the modes of its use, what I claim is:

45 1. A tool for removing plaits or wrinkles from the toes of boots and shoes, comprising

ing a rotatable body or hub, a circular series of parallel rods or pintles carried thereby, and a plurality of pounding and wiping members loosely hung upon said rods or 50 pintles, said members having flat operative faces and being composed of relatively flexible cushioning material adapted to frictionally engage the toe portion of the upper, when the tool is rotated. 55

2. A tool for removing plaits or wrinkles from the toes of boots and shoes, comprising a rotatable body or hub, a circular series of parallel rods or pintles carried thereby, and a plurality of pounding and wiping members 60 loosely hung upon said rods or pintles, and constructed and arranged both to swing thereon and to move bodily relatively thereto, each of said members comprising an inner stiff layer and outer layers of cushioning 65 material.

3. A tool of the character described, comprising a rotatable hub having circumferential flanges at the ends thereof, a circular series of parallel rods socketed in said 70 flanges, a series of substantially radial operating members each consisting of a cushioning friction material doubled over one of said rods between said flanges, and a layer of stiffer material intervening between 75 the layers of folded portions of said first-mentioned material, and means for fastening said layers together.

4. A tool of the character described, comprising a rotatable hub, a circular series of 80 parallel rods carried thereby, and a series of pounding and wiping members hung loosely on said rods to extend substantially radially from said hub when the latter is being rotated, each of said members having superimposed layers of material for frictionally engaging and wiping the work, each of said members comprising two or more connected relatively movable sections or tabs. 85

In testimony whereof I have affixed my 90 signature.

ORVILLE W. EWING.
